UNITED STATES PATENT OFFICE.

CHARLES HAGUE, OF HOT SPRINGS, ARKANSAS.

FENCE STRETCHER.

Application filed August 25, 1921. Serial No. 495,197.

To all whom it may concern:

Be it known that I, CHARLES HAGUE, a citizen of the United States, residing at Hot Springs, in the county of Garland and State 5 of Arkansas, have invented a new and useful Fence Stretcher, of which the following is a specification.

This invention relates to stretchers especially designed for use in connection with 10 wire fabric fences so that they can be pulled taut and held and thus properly secured to the posts of the fences.

Another object is to provide a simple and compact structure which can be operated by 15 hand without requiring excessive exertion.

Another object is to provide a stretcher of this character which can be readily collapsed when not in use, can be easily adjusted, and will not easily get out of order.

20 With the foregoing and other objects in view which will appear as the description proceeds, the invention resides in the combination and arrangement of parts and in the details of construction hereinafter described and claimed, it being understood that, within the scope of what is claimed, changes in the precise embodiment of the invention shown can be made without departing from the spirit of the invention.

30 In the accompanying drawings the preferred form of the invention has been shown.

In said drawings—

Figure 1 is a side elevation of the stretcher in use.

35 Figure 2 is an elevation of the operating mechanism viewed at right angles to Figure 1.

Figure 3 is a section on line 3—3, Figure 1.

40 Figure 4 is a section on line 4—4, Figure 1.

Referring to the figures by characters of reference 1 designates a bar constituting one end of the stretcher, this bar being provided 45 near its ends with eye bolts 2 to which are secured the ends of a chain 3 or the like adapted to be suitably fastened, as shown at 4, to a fence post P.

Bolted or otherwise secured to the ends 50 of the bar 1 are parallel guide strips 5 each of which has a longitudinal series of apertures 6. A fixed cross head 7 is provided with forked ends 8 which straddle the respective strips 5 and are held against movement along said strips and away from the bar 55 1 by stop pins 8' which are inserted into cer-

tain of the openings 6. A bushing 9 is mounted within the central portion of the bar 7 and constitutes a bearing for one end portion of a feed screw 10, this screw being swiveled 60 within the bushing or being held in any other suitable manner against longitudinal movement relative to the bushing. A bracket 11 is fastened to the cross head 7 and mounted on the feed screw between this 65 bracket 11 and the cross head is a gear 12 adapted to rotate with the feed screw. An operating shaft 13 is journaled in the cross head 7 and the bracket 11 and has a crank arm 14 or the like whereby it can be rotated 70 readily. A train of gears 15 is employed for transmitting motion from this shaft 13 to the gear 12, these gears increasing in size so as to give increased power from shaft 13 to the screw 10. 75

A movable cross head 16 is slidably on and straddles the strips 5 and is provided at its center with a nut 17 engaged by the feed screw 10. Thus it will be seen that by rotating the feed screw the movable cross head 80 16 can be shifted toward or from the cross head or bar 7.

A clamping bar 18 formed of parallel strips indicated at 19 in Figure 4 is slidably mounted at its ends on the strips 5 and has 85 bolts 20 connecting the strips so that when one end of a wire fabric is inserted between the strips 19 these bolts 20 can be tightened so as to clamp the strips upon the fabric. Eye screws or the like are fastened to one 90 of the strips 19 as shown at 21 and similar eye screws 22 or the like are fastened to the cross head 16. Coupling links or rods 23 connect the eye screws 21 and 22 so that motion will be transmitted to the clamping bar 95 18 from the cross head 16.

Coiled springs 24 may be attached to the end portions of one of the strips 19 and can also be fastened to a fence post P. Thus it will be seen that during the application of 100 the stretcher to a fence fabric the said stretcher can be yieldingly supported in operative position between two posts by the springs 24 and the chain 3. When the bar 18 is applied to the fence fabric F it is preferably located between the free ends of the strips 5 and the cross heads 7 and 16 are located as far apart as permissible. The cross head 7 is held against movement toward the head 16 by the pins 8. After the bar 18 has 110 been applied properly to the fence fabric the gears are rotated by means of crank 14 and

the feed screw 10 will thus draw the cross head 16 toward the cross head 7 and cause the rods 23 to pull on bar 18 and the fabric attached thereto. The fabric will thus be 5 stretched evenly and while held can be fastened to those posts past which it extends.

When the apparatus is not in use the clamping bar 18 and the cross heads 7 and 16 can be removed from the strips 5 and said 10 strips can be detached from the ends of the bar 1. Thus the entire structure can be stored in a small space.

It will be understood that during the stretching operation the supporting springs 15 24 will yield to permit the bar 18 to move under the action of the feed screw 10.

Under some conditions the springs 24 can be dispensed with if so desired.

What is claimed is:—

- 20 1. A device of the class described including connected guide strips, means for anchoring them to a fence post, a normally stationary cross head adjustably mounted on the guide strips, a feed screw supported thereby, power multiplying means carried 25 thereby, power multiplying means carried by said cross head for actuating the feed screw, a movable cross head mounted on the guide strips for actuation by the feed screw, means slidably on the guide strips for engaging a fence fabric, and a connection be-

tween said means and the movable cross head.

2. In a device of the class described the combination with connected guide strips and means for anchoring the same to a fence 35 post, of a cross head straddling the respective guide strips, means for holding the cross head adjustably to the strips, a feed screw carried by the cross head, power multiplying means upon the cross head for actuating the feed screw, a cross head engaged and actuated by the feed screw and slidably mounted on the guide strips, a clamping bar slidably engaging the guide strips for attachment to a fence fabric, connections between the clamping bar and the movable cross head, and yieldable means for connecting the clamping bar to a fence post to support the guide strips at one end, said yielding means being expansible by the movement of the clamping bar during the stretching of a fence fabric.

In testimony that I claim the foregoing as my own, I have hereto affixed my signature in the presence of two witnesses.

CHARLES HAGUE.
